APPARATUS FOR ACETYLENE PRODUCTION BY
PARTIAL COMBUSTION OF HYDROCARBONS

4 Claims. (Cl. 23—277)

My invention relates to the production of acetylene by partial combustion of gaseous hydrocarbons, particularly methane or its higher homologues, with oxygen.

The equipment used for such production comprises a mixer to which methane and oxygen, separately preheated, are supplied, and a reaction chamber wherein the methane burns in form of an inverted flame which is rapidly extinguished with a water jet.

In order to prevent propagation of the flame from the combustion chamber to the mixing chamber, a distributor is interposed. It consists of a properly cooled steel plate vertically traversed by numerous parallel tubes in which the gas flow has a speed higher than the speed of flame propagation.

As the tubes are parallel, the speed of gas in the zone closely above the top surface of the distributor will necessarily be lower than the speed of the flame propagation. Thus, if accidental causes lead to ignition of the mixture upstream of the distributor, all of the gaseous mass contained in the mixing chamber, may also become ignited, thus resulting in irreparable damages to the apparatus.

It is an object of my invention to obviate such danger. My invention essentially consists of providing a gas distributor, which separates the mixing chamber from the combustion chamber, so that the speed of gas upstream the distributor is higher than the speed of flame propagation, and is illustrated by the drawing.

Methane or a higher homolog thereof and oxygen, respectively preheated in heaters 1 and 2, are introduced from above to mixer 3, at a speed greater than that of flame propagation, so that in the event of ignition the flame could not remain in the tube but would be immediately blown down. The distributor 4 is formed by two steel plates, which are preferably spherical, connected by numerous steel tubes 13; the top plate 9 has a smaller surface than the bottom plate 10. When the steel plates are spherical, the tubes connecting the two plates diverge.

The ratio between the diameter of the top and bottom plates is so calculated that the speed of gas near the top plate and in the connecting tubes is higher than the speed of flame propagation, whereas the speed of gas in the combustion chamber is much less than the speed of flame propagation. With my apparatus as described, it is possible to maintain a constant and regular flame which remains at the lower surface of the distributor.

The relationship existing between the upper and lower surface areas of the pipe-distributor of the burner is as follows (said areas being proportional to the squares of the respective diameters d and D):

$$0 < \left(\frac{d^2}{D^2} = f \right) < 1$$

wherein d and D are respectively the diameter of the upper and lower surfaces and f is the ratio between the square of the diameters, and is greater than 0 but less than 1 and represents a fraction which is the reciprocal of the pressure, that is, a function

$$f = f'(1/p)$$

and is an experimental correlation giving f a numerical value equal to

$$0 < f < 1$$

2

in the meaning that with an increase of pressure there is a reduction of the factor f .

The mixture of hydrocarbon and oxygen affords easier preignitions and higher velocities of flame propagation, the higher the cracking pressure. Hence the higher the cracking pressure, the smaller must ratio d^2/D^2 be and correspondingly the greater the velocity of the gas entering at top of the distributor with respect to the velocity of the gas leaving at bottom where the flame appears. This ratio preferably assumes values comprised within the following limits:

$$0.2 < \frac{d^2}{D^2} < 0.8$$

Water is circulated under pressure by pump 5 between the diverging tubes, in order to ensure the cooling of the lower plates. The cooling water after being heated is recycled through line 12 to storage tank 14 from where small quantities of steam are permitted to enter the oxygen preheater 2.

Other variations of the distribution are possible provided the relationship of

$$0.2 < \frac{d^2}{D^2} < 0.8$$

is maintained. For instance, the plates need not be spherical but could be planar. Alternatively, for instance, the following structures may be adopted: (a) a structure quite analogous to that described above but wherein the pipes for the outflow of the gas mixture project from the top plate of the distributor and the spaces between the pipes are filled with refractory; (b) another structure having steel pipes 13 embedded over their whole lengths in a suitable refractory whence neither the top metal plate nor the bottom metal plate are any longer needed: in that case the line 11 may be connected directly to the storage vessel 14, no cooling being any more required; (c) a further structure with which not only the top and bottom plates but also the steel pipes 13 are dispensed with, the conduits for the gas mixture being provided in the very refractory; here too the line 11 leads directly to the storage vessel 14.

By using, for example, water at a pressure, of say 16 atmospheres which corresponds to a boiling temperature of 200° C., the mechanical stresses on the cooled metal walls, because of thermal expansion, are much less than by using cold water.

One of the more troublesome difficulties in the production of acetylene through partial combustion of methane or other hydrocarbons with oxygen, is the formation of carbon black. I have found that the formation of carbon black may be effectively reduced if a small quantity of steam is added to the reacting gases. For example, the addition of 10 kg. of steam per 100 Nm.³ of methane is sufficient for reducing to $\frac{1}{3}$ the production of carbon black without any effect on the acetylene yield. The steam may be added to the oxygen and/or methane prior to their reentry into preheaters 1 and 2 or into the mixer 3. The quantity of steam may vary between 2 and 20 kg. per 100 Nm.³ of CH₄ although about 10 kg. is preferable. The presence of steam also gives greater safety against self-ignition of the methane-oxygen mixture particularly when under pressure, thus reducing the probability of a premature gas combustion in the mixing chamber.

The technique, generally used in the conventional acetylene production process for stabilizing the flame, consists in introducing small quantities of oxygen (secondary) through the cooled walls of the combustion chamber, near the reaction priming zone; but it is known that such a technique has the effect of greatly reducing the

acetylene yield. I have found, however, that this great reduction is avoided when the combustion is stabilized through a series of small oxy-hydrogen flames (secondary), obtained by burning hydrogen with oxygen through the nozzles 7 placed near the lower plate of the distributor. The gaseous mixture flowing from the reaction chamber is suddenly cooled with water injected by the sprayer 8, according to known techniques.

The following table illustrates the cracking conditions in the presence of:

- (a) methane+primary and secondary oxygen
- (b) methane+primary and secondary oxygen+steam
- (c) methane+primary oxygen and hydrogen+secondary oxygen

are shown by the following proportions between the flow rates of the reactants employed and the respective flow rates of the reactants employed and the respective results obtained; wherein Nm.³ is cubic meters calculated at normal conditions:

Table

Case	(a)	(b)	(c)
Flow rate of CH ₄ , Nm. ³ /hr	250	250	380
Temperature of CH ₄ preheating, °C	550	550	550
Flow rate of primary O ₂ , Nm. ³ /hr	140	145	210
Temperature of prim. O ₂ preheating, °C	550	550	550
Flow rate of secondary O ₂ , Nm. ³ /hr	1	1	—
Temperature of secondary O ₂ , °C	30	30	—
Flow rate of steam, kg./hr	—	20	—
Preheating temperature of steam, °C	550	—	—
Flow rate of H ₂ , Nm. ³ /hr	—	55	—
Temperature of H ₂ , °C	—	30	—
Flow rate of O ₂ with H ₂ , Nm. ³ /hr	—	—	25
Temperature of O ₂ with H ₂ , °C	—	—	30
Cracking pressure, abs. atm.	4	4	4
Carbon black content in quenching water, g./litre	0.45	0.15	0.04
Acetylene yield, Kg. of C ₂ H ₂	16.8	17.0	17.8
100 Nm. ³ of CH ₄	—	—	—
100 Nm. ³ of CH ₄	—	—	—

I claim:

1. In an apparatus for the production of acetylene by the partial combustion of hydrocarbons with oxygen having a gas mixing chamber and a combustion chamber; a gas distributor interconnecting the gas mixing chamber and the combustion chamber, said gas distributor comprising a lower metal plate, an upper metal plate and tubes of constant diameter interconnecting said plates for gas passage from the gas mixing chamber to the combustion chamber, the area of the upper of said metal plates being from 0.2 to 0.8 the area of the lower of said plates,

which are spherical and concentric, said tubes being evenly spaced and diverging from the upper to the lower plates, a water jacket about the tubes and disposed between the plates for introducing water under pressure to cool said tubes and produce steam, a row of oxy-hydrogen burners at the lower of said plates to stabilize the flame produced by said partial combustion, and quench means downstream of said oxy-hydrogen burners for quenching said combustion.

10 2. The apparatus of claim 1, which includes means for passing the steam, produced in the water jacket, to the gas mixing chamber.

15 3. In an apparatus for the production of acetylene by the partial combustion of hydrocarbons with oxygen having a gas mixing chamber and a combustion chamber; a gas distributor interconnecting the gas mixing chamber and the combustion chamber, said gas distributor comprising a lower metal plate, an upper metal plate and tubes of constant diameter interconnecting said plates for 20 gas passage from the gas mixing chamber to the combustion chamber, the area of the upper of said metal plates being from 0.2 to 0.8 the area of lower of said plates, which are planar and parallel, said tubes being evenly spaced and diverging from the upper to the lower plates, 25 a water jacket about the tubes and disposed between the plates for introducing water under pressure to cool said tubes and produce steam, a row of oxy-hydrogen burners at the lower of said plates to stabilize the flame produced by said partial combustion, and quench means produced downstream of said oxy-hydrogen burners for quenching said combustion.

30 4. The apparatus of claim 3 which contains means for passing the steam, produced in the water jacket, to the gas mixing chamber.
